CARVING APPARATUS

Judson M. Holcomb, Alhambra, Calif.

Application March 21, 1942, Serial No. 435,693

11 Claims. (Cl. 90—13.2)

This invention relates to a carving apparatus. The general object of the invention is to provide a novel carving apparatus which will permit an operator to carve a block of wood, metal, or other material to a configuration corresponding to a pattern over which the operator moves a tracer point.

A further object of the invention is to provide a novel support means for the cutting tool and tracing member of a carving apparatus.

A further object of the invention is to provide a novel support for the tracing member of a carving apparatus.

Another object of the invention is to provide a novel counterbalance for the working head of a carving apparatus.

Other objects and advantages of this invention will be apparent from the following description taken in connection with the accompanying drawings, wherein:

Fig. 1 is a side elevation showing my improved carving apparatus;

Fig. 2 is a fragmentary side elevation on an enlarged scale and with parts broken away showing the working head and associated parts;

Fig. 3 is a section taken on line 3—3, Fig. 2 and with parts broken away;

Fig. 4 is a top plan view of the carriage with parts broken away;

Fig. 5 is a section taken on line 5—5, Fig. 4; and

Fig. 6 is a front elevation showing the support frame.

Referring to the drawings by reference characters, I have shown my invention as embodied in a carving apparatus which is indicated generally at 10. As shown the apparatus is mounted on a frame indicated generally at 11 and which includes vertical corner posts 12 connected by upper, lower and intermediate transverse members 13 and by a pair of upper longitudinal members 14 and a lower longitudinal member 15. The upper intermediate transverse members 13 support a work table 16 while the lower intermediate members 13 support a pattern holding table 17. The tables 16 and 17 may be provided with longitudinal slots 18 through which clamping members are inserted to hold the work 19 and the pattern 20 in place.

The frame is preferably made of wood and includes vertical supports 21 arranged on the member 15 and engaging a transverse member 22 beneath the table 17. Diagonal braces 23 connect the member 15 and the lower intermediate member 13.

The upper longitudinal members 14 are spaced apart and are preferably rectangular so that they provide upper track surfaces 24 and inner track surfaces 25. The upper track surfaces 24 are engaged by rollers 26 mounted on shafts 26 which are supported on a carriage 27 which moves between the members 14. The carriage 27 includes rollers 28 mounted on vertical shafts 29. The rollers 28 engage the inner track surfaces 25 so that the carriage is supported and guided by the rollers 26 and 28.

The carriage 27 supports a depending rod 30 which rotatably mounts a support frame indicated generally at 31. (Figs. 4 and 5). This support frame 31 includes spaced side members 32, an upper member 33 and a bottom member 34 with the members suitably joined together.

A support member 35 is arranged between the members 33 and 34 and on this support member I mount a front track member 36 and a rear track member 37.

A working head is arranged between the side members 32. This working head includes converging sides 38 and 39, a front end 40 and a rear end 41. The working head is adapted to move vertically up and down and is provided with brackets 42 which support rollers 43 engaging the track member 36. The working head is also provided with brackets 44 which support rollers 45 which engage the track member 37.

The sides 32 are also provided with brackets 46 which support rollers 47 and these rollers 47 engage track members 48 mounted on the sides 38 and 39 of the working head. As shown in Fig. 3, the track members 36 and 37 are of such a length that they may move between the sides 38 and 39 of the working head.

On the front end 40 of the working head I show a bearing block 49 which supports a shaft 50 which in turn supports a chuck 51 adapted to hold a cutting tool 52. A shaft 50 supports a pulley 53 adapted to be driven by a belt 54 from a pulley 55 mounted on the armature shaft 56 of a motor 57. The base 58 of the motor 57 is held by bolts 59 on the rear end 41 of the working head. The working head includes a switch housing 60 with a switch handle 61 thereon and with a lead 62 for supplying current to the motor.

In order to provide a counter-balance for the working head, each side member 32 is provided with an upper pair of aligned outwardly projecting shafts 63 and with a lower pair of aligned

outwardly projecting shafts 64. On the shafts 63 I pivot bars 65. The bars 65 extend forwardly and are connected by a shaft 66 which supports a counterweight 67. The bars 65 also extend rearwardly and are connected beyond the rear end 41 by a rod 68. The upper rear edge of the bars 65 are engaged by rollers 69 mounted on pins 10 carried by the working head.

Each of the shafts 64 supports a lower bar 71. The lower bars 71 are connected by a shaft 72 which supports a counterweight 73. The front ends of the bars 71 are connected by a crossbar 74 which extends through slots 75 in the sides 38 and 39 in the working head. The cross bar 74 slides along a guide plate 77 mounted on each side 38 and 39. The counterweights 67 and 73 are of such weight that they balance the working head thus allowing the working head to be moved vertically with a minimum of effort.

The working head is provided with a shield 78 which may be made of sheet metal and is held in place by fastening members 79. The shield 78 surrounds the pulley 53 and the chuck 51.

Mounted on the front end 40 of the working head I show a downwardly directed loop member 80 which surrounds the work table 16. A fitting 81 is secured on the loop member 80 as by welding at 82. The fitting 81 includes a removable tracing point 83 which is vertically aligned with the tool 52.

The loop member 80 is provided with a pair of spaced brackets 84 held in place by bolts 85. The brackets are connected to a brace member 86 disposed on both sides of the pattern holding table 17 and extending rearwardly and secured to the end member 41 by L-shaped bracket 87. The brackets 87 are held in place by bolts 88. The loop member 86 is braced by a diagonal member 89 secured at 90 to each side 38 and 39 of the working head. The lower end of each brace 89 is secured to the loop member 86 as by a bolt 91.

In the use of my device the work 19 and the pattern 20 are secured in place by suitable means not shown. The tracer point 83 being in place, the cutting tool 52 is adjusted to the proper vertical position and the switch 61 is adjusted to start the motor. The tracing point is then moved over the pattern, and as it is moved, the cutting tool 52 moves also so that the work 19 is carved to correspond to the pattern 20.

The tracing point and cutting tool rotate about the vertical axis of the rod 30 and also move simultaneously up and down with the working head on which they are mounted. The counterweights 67 and 73 are so proportioned that very little effort is needed to raise and lower the tracing point 83.

From the foregoing description it will be apparent that I have invented a novel carving apparatus which can be economically manufactured and which is highly effective for its intended purpose.

Having thus described my invention, I claim:

1. In a carving apparatus, a standard, a pattern support on said standard, a work support on said standard, a track member on said standard, a carriage slideable on said track member, a support frame, vertical pivot means on said carriage and supporting said frame, a working head vertically slideable on said support frame, a chuck rotatably mounted on said working head, means to drive said chuck, and a

tracing point mounted on said working head and disposed coaxial with said chuck.

2. In a carving apparatus, a base, a carriage slideable on said base, a support frame pivotally mounted on said carriage, a working head, means to shiftably mount the working head on said support frame, a tool rotatably mounted on said working head, a loop member mounted on the forward part of said working head and including a depending portion, and a tracing point on said depending portion and disposed co-axial with said tool.

3. In a carving apparatus, a base, a carriage slideable on said base, a support frame pivotally mounted on said carriage, a working head, means to shiftably mount the working head on said support frame, a tool rotatably mounted on said working head, a work support, a loop member mounted on the forward part of said working head and including a lower portion movably beneath said work support, a tracing point on said lower portion and disposed co-axial with said tool, a brace member engaging said loop member and extending rearwardly therefrom and connected to the rear portion of said working head and supports engaging said brace member and the forward portion of said working head.

4. In a carving apparatus, a standard, a pattern support on said standard, a work support on said standard, a track member on said standard, a carriage slideable on said track member, a support frame, vertical pivot means on said carriage and supporting said frame, a working head vertically slideable on said support frame, aligned shafts on said support frame, bars pivotally mounted on said shafts, counterweights supported by said bars, guide means on said working head and slidably engaging said bars, a chuck rotatably mounted on said working head, means to drive said chuck, and a tracing point mounted on said working head and disposed co-axial with said chuck.

5. In a carving apparatus, a base, a carriage slideable on said base, a support frame pivotally mounted on said carriage, a working head, means to shiftably mount the working head on said support frame, said support frame including opposed sides, an upper and a lower shaft on each side, a bar pivotally mounted on each shaft, counterweights supported by said bars, guide means on said working head and slidably engaging said bars, a chuck rotatably mounted on said working head, means to drive said chuck, a work support, a loop member mounted on the forward part of said working head and including a lower portion beneath said work support, a tracing point on said lower portion and disposed co-axial with said tool, a brace member engaging said loop member and extending rearwardly therefrom and connected to the rear portion of said working head and supports engaging said brace member and the forward portion of said working head.

6. In a carving apparatus, a standard, a pattern support on said standard, a work support on said standard, a carriage slideable on said standard, a support frame, vertical pivot means on said carriage and supporting said frame, a working head vertically slideable on said support frame, a pair of aligned shafts on said support frame, a bar pivotally mounted on each shaft, said bars extending forwardly and rearwardly of said shafts, a counterweight supported at one end of said bars, means on said working head and slidably engaging said bars, a second pair of aligned

shafts on said side members, other bars mounted on each of said second shafts, said other bars extending rearwardly from said second shafts, a counterweight mounted on one end of said other bars, a chuck rotatably mounted on said working head, means to drive said chuck, and a tracing point mounted on said working head and disposed coaxial with said chuck.

7. In a carving apparatus, a standard, a pattern support on said standard, a work support on said standard, a track member on said standard, a carriage slidable on said track member, a support frame, vertical means pivotally supporting said support frame on said carriage and supporting said frame, a working head vertically slidable on said support frame, a pair of aligned shafts on said support frame, a bar pivotally mounted on each shaft, said bars extending forwardly and rearwardly of said shafts, a counterweight supported at one end of said bars, brace means connecting the other ends of said bars, means on said working head and slidably engaging said bars, a second pair of aligned shafts on said side members, other bars mounted on each of said second shafts, said other bars extending rearwardly from said second shafts, a counterweight mounted on one end of said other bars, means connecting the other ends of said other bars, said last mentioned means including portions slidably engaging said working head, a chuck rotatably mounted on said working head, means to drive said chuck, and a tracing point mounted on said working head and disposed co-axial with said chuck.

8. In a carving apparatus, a standard, a pattern support on said standard, a work support on said standard, track members on said standard, a carriage slidable on said track members, a support frame supported on said carriage for movement about a vertical axis, a working head vertically slidable on said support frame, a pair of aligned shafts on said support frame, a bar pivotally mounted on each shaft, said bars extending forwardly and rearwardly of said shafts, a counterweight supported at one end of said bars, brace means connecting the other ends of said bars, guide means on said working head and slidably engaging said bars, a second pair of aligned shafts on said side members, other bars mounted on each of said second shafts, said other bars extending rearwardly from said second shafts, a counterweight mounted on one end of said other bars, means connecting the other end of said other bars, said last mentioned means including portions slidably engaging said working head, a chuck rotatably mounted on said working head, means to drive said chuck, a loop member mounted on the forward part of said working head and including a lower portion beneath said work support, a tracing point on said lower portion and disposed co-axial with said chuck, a brace member engaging said loop member and extending rearwardly therefrom and connected to the rear portion of said working head and supports engaging said brace member and the forward portion of said working head.

9. In a carving apparatus, a standard, a pattern support on said standard, a work support on said standard, a track member on said standard, a carriage slidably mounted on said track members, a depending support frame pivotally supported on said carriage, a hollow working head slidably mounted on said support frame, rollers mounted on said support frame and engaging said head to prevent lateral movement thereof, a guide member mounted on said support frame,

said guide member including spaced vertical track surfaces, rollers mounted on said working head and engaging said vertical track surfaces to prevent front and rear movement of said working head, a pair of aligned outwardly extending upper shafts on said support frame, a bar pivotally mounted on each shaft, said bars extending forwardly and rearwardly of said shafts, a counterweight supported on the forward ends of said bars, brace means connecting the rear ends of said bars, rollers on the rear portion of said working head and engaging said bars, a second lower set of outwardly extending aligned shafts on said support frame, a lower bar mounted on each of said second shafts, said lower bars extending rearwardly and forwardly from said second shafts, a counterweight mounted on the rear ends of said second bars, means connecting the front ends of said second bars, said last mentioned means extending through said working head and including portions slidably engaging said working head, a chuck rotatably mounted on the forward portion of said working head, a motor mounted on said working head, means whereby said motor drives said chuck, a loop member mounted on the forward part of said working head and including a lower portion beneath said work support, and a tracing point on said lower portion and disposed co-axial with said chuck.

10. In a carving apparatus, a standard, a pattern support on said standard, a work support on said standard, a track member on said standard, a carriage slidably mounted on said track members, a support frame pivotally supported on said carriage, a hollow working head slidable within said support frame, rollers mounted on said support frame and engaging said head to prevent lateral movement thereof, a guide member mounted on said support frame and disposed within said working head, said guide member including spaced vertical track surfaces, rollers mounted on said working head and engaging said vertical track surfaces to prevent front and rear movement of said working head, a pair of aligned outwardly extending upper shafts on said support frame, a bar pivotally mounted on each shaft, said bars extending forwardly and rearwardly of said shafts, a counterweight supported on the forward ends of said bars, brace means connecting the rear ends of said bars, rollers on the rear portion of said working head and engaging said bars, a second lower set of outwardly extending aligned shafts on said support frame, a lower bar mounted on each of said second shafts, said lower bars extending rearwardly and forwardly from said second shafts, a counterweight mounted on the rear ends of said second bars, means connecting the front ends of said second bars, said last mentioned means extending through said working head and including portions slidably engaging said working head, a chuck rotatably mounted on the forward portion of said working head, a motor mounted on said working head, means whereby said motor drives said chuck, a loop member mounted on the forward part of said working head and including a lower portion beneath said work support, a tracing point on said lower portion and disposed co-axial with said chuck, a brace member engaging said loop member and extending rearwardly therefrom and connected to the rear portion of said working head and supports engaging said brace member and the forward portion of said working head.

11. In a carving apparatus, a standard, a pattern support on said standard, a work support on said standard, a pair of spaced horizontal track members on said standard, each track member including a vertical track surface and a horizontal track surface, a carriage, rollers mounted on said carriage and engaging said track surfaces, a depending rod mounted on said carriage, a support frame including spaced side members, an upper member and a bottom member, pivotally supported on said rod, a working head, rollers mounted on said side members and engaging said head to prevent lateral movement thereof, a guide member mounted on said upper and lower frame members and disposed within said frame, said guide member including spaced vertical track surfaces at each side thereof, rollers mounted on said working head and engaging said last mentioned vertical track surfaces to prevent front and rear movement of said working head, a pair of aligned, outwardly extending, upper shafts on said side members, a bar pivotally mounted on each shaft, said bars extending forwardly and rearwardly of said shafts, a

5 counterweight supported on said bars, brace means connecting the rear ends of said bars, rollers on the rear portion of said working head and engaging said bars, a second lower set of outwardly extending aligned shafts on said side members, a lower bar mounted on each of said second shafts, said lower bars extending rearwardly and forwardly from said second shafts, a counterweight mounted on said second bars, means connecting the front ends of said second bars, said last mentioned means extending through said working head, a chuck rotatably mounted on said working head, a motor mounted on said working head, means whereby said motor drives said chuck, a loop member mounted on the forward part of said working head and including a lower portion beneath said work support, a tracing point on said lower portion and disposed co-axial with said chuck, and a brace member engaging said loop member and extending rearwardly therefrom and connected to the rear portion of said working head.

JUDSON M. HOLCOMB.
